Specification for Design.

Patented Dec. 18, 1917.

Application filed August 1, 1914. Serial No. 854,577. Term of patent 14 years.

To all whom it may concern:

Be it known that I, ERNEST S. SUTTON, a citizen of the United States, residing at Memphis, Shelby county, and State of Tennessee, have invented a certain new, original, and ornamental Design for a Bottle, of which the following is a specification.

The accompanying drawing which is made a part hereof and to which reference is made, shows in side elevation the shape and style of the bottle and the ornamental characteristics thereof forming the subject matter hereof.

What I claim is:

The ornamental design for a bottle shown in the accompanying drawing.

In witness whereof, I have hereunto set my hand and seal at Memphis, Tennessee, this 30th day of June, A. D. nineteen hundred and fourteen.

ERNEST S. SUTTON. [L. S.]
